UNITED STATES PATENT OFFICE

ANTHONY H. G. FOKKER, OF TENAFLY, NEW JERSEY

METHOD AND MEANS OF OPERATING AIRLINES

Application filed September 27, 1928. Serial No. 308,815.

This invention relates generally to the operation of aircraft, especially in so-called commercial services, and is more particularly directed to the provision of means for facilitating the embarkation and discharge of passengers at airports, as the terminals and intermediate stations of airlines, and for controlling the movement of the passengers to and from the airplane, so as to 10 safeguard them from the possibility of accident.

As is well known, at airports where passengers are taken on and discharged from airplanes, there is no provision made for 15 expediting the handling of the passengers, in the manner customarily followed by other transportation agencies, the craft usually being lined up in the open field, frequently at a considerable distance from the hangars, 20 where they are surrounded by onlookers who crowd about the passengers and retard their progress to and from the craft. Further, there is no method of controlling the movements of the passengers, or of the on- 25 lookers, upon the field or about the airplane, and, in many instances, serious and usually fatal injuries have resulted from persons attempting to pass in front of a moving plane, or from coming in contact with a re- 30 volving propeller of a craft at rest upon the field. In some cases, portions of the field at an airport, have been roped off, but, at best, this is nothing more than a makeshift effort in the interest of safety. The 35 ropes, which are usually tied to insecure stakes are soon overrun and conditions are no better than where such impractical safeguards are not employed. In other instances, attempts have been made to reduce 40 the danger of accident, by employing a large force of watchmen to protect the aircraft and also the persons on the field, but in the operation of an airline, this, obviously, is impracticable from an economic stand- 45 point.

While it has been recognized that there is a necessity for providing for the handling of passengers and for reducing the hazards, at airports, no steps toward the practical solution of either of these problems have been

taken, and, therefore, it is the general object of this invention to provide a practical and efficient method and means of economically handling airplane passengers at airports, so as to safeguard them against the 55 possibility of accident during their embarkation and discharge from the craft.

More specifically, it is an object of this invention to provide a means for facilitating the loading and unloading of an airplane at an airport, by controlling the movement of the passengers to and from the craft, such controlled movement insuring the passengers against accidental or other contact with a revolving propeller of the 60 plane.

It is also an object of my invention, to provide a means for guiding an airplane to a predetermined position for taking on or discharging passengers at an airport or 65 landing field, whereby the work to be performed will be expedited and the operation of the craft in landing or preparatory to taking off will not be interfered with by the usual onlookers.

My invention further contemplates the provision of means which will serve to define the ground course or path which an airplane landing at an airport must follow 70 to the point where its movement must be arrested for unloading, or loading, as the case may be.

Another important object of my invention is the provision of means, as aforesaid, which will have a wide range of adjustability in use, so that they may be utilized in conjunction with various types of aircraft, and efficiently respond to the diverse requirements of operation at different airports or 75 landing fields.

Other objects and advantages flowing from the practicing of my invention will become manifest as the description proceeds and I would have it understood that I reserve unto myself all rights to the full 80 range of equivalents, both in structure and in use, to which I may be entitled under my invention in its broadest aspect.

For the purpose of the present disclosure, I have elected to illustrate and describe cer- 100

tain preferred embodiments of my invention. However, this is not to be construed as a limitation of the scope of the invention, which, it will be obvious, may take other forms, within the purview of the appended claims.

5 In the accompanying drawings:

Figure 1 is a top plan view of a practical embodiment of my invention, showing a passenger platform, with a fragment of a station building and the means for controlling the movement of the passengers to and from the airplane, a part of the wing of which is broken away, disclosing the guideway for the craft.

10 Figure 2 is a front elevation of the station building, with an airplane in position for loading or unloading, part of one of the passenger movement controlling devices being seen in elevation.

20 Figure 3 is a side elevation of the structure shown in Figure 2, looking at the tail of the airplane, showing the devices for controlling the movement of the passengers to and from the plant, in functioning position, and

25 Figures 4 and 5 are views similar to Figure 3, showing modified constructions of the passenger movement controlling devices.

30 Referring now to the drawings in detail, in which like characters of reference are employed to designate similar parts in the several views, 7 indicates the station building which may be of any suitable size and construction and may be provided with ticket offices and the usual waiting and baggage rooms. A platform 8 is positioned in front of the station building 7, egress from the latter to the platform being had through a suitable 35 passageway 7^a. The platform 8 may be constructed of any suitable material, such as concrete, wood or the like, preferably oblong in shape and of a length corresponding approximately to that of a predetermined section of an airplane, as and for the purposes 40 which hereinafter will become apparent.

45 Each of the shorter sides of the platform 8 is provided with suitable fencing extending from the aforesaid station building 7 to the front end of the platform. This fencing, which may be of any preferred height, may include the posts 10 and 10^a and the top and bottom rails 11 and 12, connected by the uprights or fillers 13, and, if desired, 50 wire netting or a lattice structure may extend upwardly from the top rail 11 thereof, to a line at the level of the roof of the building 7.

55 Preferably hinged to the posts 10 and 10^a respectively, for rotation through an arc of 90°, are gate-forming sections of fencing 14 and 14^a, these two sections, when in one of their two extreme positions, being adapted to meet and extend across the platform 8, 60 in parallel with the front edge thereof, to

cooperate with the side fencing and the station building at the rear of the platform, to form an enclosure for the latter, with which communication may be had only through the aforesaid passageway 7^a.

70 Now, as an airplane comes to rest in front of the platform 8, for loading or unloading, as the case may be, the aforesaid gate-forming sections 14 and 14^a are swung outwardly on their hinges to a position in which each, in effect, forms a physical continuation of the side fencing with which it is associated, their outer ends being sufficiently close to the adjacent side of the airplane fuselage to prevent the passage of persons therebetween. Thus, a clearly defined lane is provided for the movement of the passengers between the station building and the cabin entrance of the craft. Obviously, suitable stops are provided to limit the outward movement of the 75 gate sections 14 and 14^a, so that when they are extended toward the plane, they will be rigid enough to resist any pressure to which they may be subjected during the embarkation and discharge of passengers. Where 80 it is desired, the outer ends of the sections 14 and 14^a may be provided with fastening devices which will cooperate with elements which may be affixed to the side of the airplane fuselage to lock the gate-forming sections thereto and prevent possible attempts 85 at unauthorized passage between the ends of the gate sections and the fuselage. By the provision of the said gate-forming sections 14 and 14^a, movable as described, two purposes are served; Firstly, when the gates are closed, the intending passengers are prevented from leaving the platform 8 until the craft on which they are to embark is safely at rest in front of the station building 90 and secondly, when they are open or extended, persons to and from the cabin of the craft are compelled to remain within the enclosure formed by the building 7, the side fencing and associated gate sections 14 and 14^a and the side of the airplane contiguous 95 to the outer ends of said sections. Thus, interference with the activities of the crew about the ship is prevented and the passengers are safeguarded from the possibility of 100 injury as the result of accidentally coming into contact with a revolving propeller, the danger of accidents of the latter type being, 105 obviously, greater in multi-engine airplanes, where the engines are supported from the wing or otherwise, slightly in advance of the forward part of the cabin, than in craft of the single motor design.

110 The length of the platform 8 in those cases where airplanes of a comparatively 115 uniform fuselage length are loaded and unloaded, corresponds generally to the distance between a point slightly forward of the cabin entrance and a point just in advance of the tail surface, as shown in Figure 120 125

ure 1, so that when the gate-forming sections are swung outwardly, the passengers will have ample room for moving about within the prescribed safety limits. Where it is desired, or necessary, the passageway from the platform 8 to the cabin of the craft, as defined by the gate-forming sections 14 and 14^a, may be slightly wider than the cabin entrance the ends of said sections meeting the fuselage on either side of such entrance. For this purpose, or to provide for the accomodation of ships of different cabin and fuselage dimensions at a single loading and unloading station, the side fencing may be laterally adjustable along the platform 8, or such fencing may be fixed and the gate-forming sections 14 and 14^a may be relatively adjustable, either wholly or in part, to provide an aisle or passageway of the required site width between the platform and the airplane fuselage entrance. As an example, the spacing between the outer ends of the gate-sections 14 and 14^a may be reduced by rotating them through a smaller arc than heretofore described, so that they will form an angle with their respective supporting fences on the platform 8, simulating the outline of a funnel, with the outlet at the cabin door of the craft, or said sections may comprise two or more units connected for relative movement to form a passenger guiding partition of any desired or required shape. Again, the gate-forming sections 14 and 14^a may be longitudinally extensible, either of the folding type, shown in Figures 2 and 3, or with the telescoping members, as shown in Figure 4. This will admit of the outer ends of said sections being disposed relatively close to, or in contact with, the airplane fuselage, to form a safety zone, as heretofore described, in such cases where variations in the distance between the front of the platform and the aircraft might render non-extensible gate-forming sections ineffective for the purpose.

As a guide to the pilot in properly locating his craft at an airport station, the field adjacent to the loading and unloading platform 8, may be provided with suitable rails 15 and 16, which extend beyond either side thereof, as shown in Figure 1, for example. These rails, which may be in the form of concrete curbing set into the ground, or which may be wood or other material, otherwise fixed against dislodgment, are laterally spaced to provide for the passage of the wheels of the undercarriage of an airplane therebetween. The intermediate section of the rails, that is, those parts which are immediately in front of the platform, are preferably parallel, while the portions on either side of such section diverge or flare outwardly to facilitate entrance to exit from the guideway.

It will be manifest that the use of the

rails 15 and 16 in conjunction with the platform 8 and means cooperating with the platform enclosure and the airplane itself, as the sections 14 and 14^a, will enable a pilot to quickly and accurately locate his craft in position for handling the embarkation and discharge of passengers in a manner which will assure a maximum of safety from possible so-called ground accidents which are now of frequent occurrence at airports. Of course, in some instances, it may be necessary to dispense with the guideway provided by the rails 15 and 16, but this will not affect the attainment of the other objectives by the use of the media described.

Also, it will be evident that the several cooperating elements of my invention may be arranged otherwise than herein described and that in conjunction therewith separating partitions may be used to direct incoming and outgoing passengers along different paths, each of which may be protected in the manner indicated. For instance, the post 17 may be the forward end of a partition through the center of the platform 8, with a section of fencing hinged thereto which will cooperate with either of the sections 14 and 14^a. Thus, if the section 14 is functioning as a closure for the part of the platform to the left of the central partition, the fence section hinged to the post 17 may be swung outwardly in parallel with the similarly disposed section 14^a and vice versa, it, of course, being understood that the aforesaid centrally located swingable section will be so mounted that it may be disposed in parallel with either of the gate-forming sections 14 and 14^a, when they are in platform closing position, as the gate section 14 in Figure 1.

I claim:

1. A loading and unloading station for airplanes at an airport, comprising a platform raised above the level of the ground and including a housing for passengers, an enclosure for said platform embodying movable sections at that portion thereof before which an airplane is to be brought to rest, said sections being extendable from said platform in the direction of an airplane to be loaded or unloaded in laterally spaced relationship to said platform to form a chutelike passage from said platform to the passenger opening in the fuselage of the airplane.

2. A loading and unloading station for airplanes at an airport, comprising a platform raised above the level of the ground and including a housing for passengers, an enclosure for said platform embodying arcuately movable sections located at that portion of the platform before which an airplane is to be brought to rest for loading and unloading, said sections being longitudinally extensible beyond the limit of

their arcuate movement in the direction of an airplane at rest in laterally spaced relationship to the aforesaid portion of said platform to enclose the ground space between the platform and the fuselage of the airplane.

3. A loading and unloading station for airplanes comprising a platform raised above the ground level and including a housing for passengers, a fence for shutting off ingress to and egress from said platform except through said housing, a portion of said fence being movable relatively to the remainder thereof outwardly of said platform and in the direction of an airplane at rest before said platform to permit passengers to pass to and fro between said platform and the airplane, said movable portion limiting the movement of the passengers to the aforesaid two directions.

4. A loading and unloading station for airplanes comprising a platform raised above the level of the ground, means laterally spaced from one edge of the platform to guide an airplane to a position which it shall assume relative to said platform for embarking and disembarking passengers, an enclosure for said platform, normally preventing access thereto except from a portion remote from the aforesaid edge, and means whereby portions of said enclosure abutting upon the aforesaid platform edge may be moved outwardly of said platform to extend the area of the enclosure to the side of an airplane in loading and unloading position before said platform.

5. A loading and unloading station for airplanes, comprising a platform raised above the level of the ground and including a housing for passengers, means on the ground in laterally spaced relation to one edge of the platform to guide an airplane to a position which it shall assume relative to said platform for embarking and disembarking passengers, enclosing means for said platform to prevent ingress to and egress from said platform except from a point remote from the aforesaid edge, portions of said enclosing means abutting upon said edge being adapted to swing outwardly from said platform to a point in close proximity to the side of an airplane at rest before said platform, said portions preventing movement of passengers toward the fore and aft portions of the airplane.

6. A loading and unloading station for airplanes comprising a platform slightly raised from the ground level and including a housing for passengers, means on the ground in laterally spaced relation to one edge of said platform to guide an airplane to a position before said platform for embarking and disembarking passengers, enclosing means for said platform to normally prevent movement to and from said plat-

form except from a point remote from the aforesaid edge and devices included in said enclosing means associated with said edge of the platform, adapted to swing outwardly therefrom for longitudinal extension across the ground to a point in proximity to said guiding means, whereby the passenger enclosure, when an airplane is at rest before said platform, will include said platform and the ground space between the aforesaid edge of the platform and an amidship section of the airplane fuselage.
